DESIGN FOR A CAMERA

Herbert D. Schmidt, Little Falls, N. J., assignor
to Emlee Sales Corp., New York, N. Y., a cor-
poration of New York

Application December 28, 1946, Serial No. 135,810

Term of patent 3½ years

(Cl. D61—1)

To all whom it may concern:

Be it known that I, Herbert D. Schmidt, a citizen of the United States, residing at Little Falls, in the county of Passaic and State of New Jersey, have invented a new, original, and ornamental Design for a Camera, of which the following is a specification, reference being had to the accompanying drawing, forming part thereof.

In the drawing:

Fig. 1 is a front elevational view of a camera showing my new design;

Fig. 2 is a side elevational view thereof;

Fig. 3 is a rear elevational view; and

Fig. 4 is a top plan view.

I claim:

The ornamental design for a camera, substan-
tially as shown.

HERBERT D. SCHMIDT.
